UNITED STATES PATENT OFFICE.

WALTER W. RIEDEL, OF DAYTON, OHIO, ASSIGNOR, BY MESNE ASSIGNMENTS, TO
DELCO-REMY CORPORATION, OF DAYTON, OHIO, A CORPORATION OF DELAWARE.

ENGINE-STARTING APPARATUS.

Application filed November 24, 1925. Serial No. 71,242.

This invention relates to improvements in a starting device for internal-combustion engines and particularly to that general form of device which includes a motor having a 5 rotatable power-transmitting member, movable transversely into engagement with the engine when the motor is rotated. Rotation of the motor is obtained by the operation of a manually-controlled element.

10 Cranking of the engine results when the rotating power-transmitting member engages said engine. When the engine becomes self-operating and rotates at a greater speed than the power-transmitting member, 15 the latter will be thrown out of engine engagement.

Generally, in devices of this kind, maintenance of the manually-controlled element in operated position will cause the rotating 20 power-transmitting member to be moved repeatedly into engagement with the faster rotating engine, which will immediately throw said member back into its disengaging position. This result is not only objectionable, 25 in that it would produce undue noise and pounding, but it might also prove damaging to the starting device.

The present invention has for its object 30 to provide a starting device of the type mentioned, equipped, however, for preventing a return of the motor into engagement with the engine after it has become self-operating and while the manually-controlled means is maintained in operated position.

35 Further objects and advantages of the present invention will be apparent from the following description, reference being had to the accompanying drawings, wherein a preferred form of the present invention is 40 clearly shown.

In the drawings:

Fig. 1 shows the starting device in normal, 45 inoperative position;

Fig. 2 is a view similar to Fig. 1. In this view the motor is shown in partly-shifted position; and

Fig. 3 is a fragmentary plan view of the starting device.

Referring to the drawings, the numeral 20 50 designates the engine flywheel. For the sake of illustration, only a portion of the engine has been shown. It will be clearly understood that the starting device could be moved into driving connection with any other suit-

able, rotatable element of the engine for 55 cranking purposes.

The starting motor comprises a housing 21 containing an armature provided with a shaft 22, journaled in the end frames of the motor housing in any suitable manner. This armature shaft extends beyond both end frames of the motor housing, each end of said shaft being pivotally mounted on the supporting platform 23. In the drawings, 60 only one end of the starting motor is shown; therefore, the description will be directed particularly to this end,—the method of mounting the end of the armature shaft not shown being substantially like the mounting 65 illustrated in the drawings.

70 Motor armature 22 has a power-transmitting element 24 secured to its one end, said power-transmitting element being shown in the form of a friction wheel. Between the friction wheel and the housing of the starting motor and journaled on the armature shaft 22, there is a link 25 which is pivotally secured to a standard 26 by means of pin 27. This standard 26 may be secured to or be formed integral with the platform 23, 75 which in turn is carried on the vehicle frame adjacent the engine in any suitable manner. From this it may be seen that the motor is pivotally supported on standards 26 by means of links 25,—duplicates of the standard 26 and link 25 being provided at the opposite end of the armature not illustrated 80 in the drawings.

85 Normally, when in inoperative position, the motor will lie at a substantial distance from an imaginary vertical line passing through its pivot pin 27. It will, of course, be understood that this inoperative position is on the side of this imaginary line opposite 90 from the engine. The motor is held in this normal, inoperative position by means of a spring bumper 28 upon which the link 25

95 is adapted to rest. This spring in turn is supported by the extension 29 formed on the standard 26, said extension forming a 100 shelf which also supports a retaining element 30. This retaining element comprises a gripper including members 31 and 32 of a resilient nature and which are adapted to grip the link 25 and hold the same in normal position, whereby jarring and shaking of the vehicle in passing over a rough road bed will not cause displacement of the motor. 105

out of normal, inoperative position. The spring 28 acts also as a shock-absorbing element when the motor is suddenly returned to its normal, inoperative position after the engine becomes self-operative.

Adjacent the standard 26 the platform 23 is provided with another standard 35 upon which the track member 36 is pivotally mounted by means of a pin 37. The standard 35 is so positioned on the platform 23 that the track element 36 will lie in the path of the power-transmitting member 24 of the starting motor. The inner edge, or more specifically that edge of the track element 36 which lies adjacent the power-transmitting element 24, is provided with a curved portion 38, circular in shape, so as to permit the said track portion 38 to fit about a portion of the circumferential edge of the power-transmitting member 24 when the track is moved into its operative position. The remaining portion of the inner edge of said track element, or that designated by the numeral 39, is so curved that when in its operative position, while the motor is still in its normal inoperative position, this edge will gradually approach the pivotal center of the motor, making this edge portion of the track eccentric to the circumferential path of travel of the power-transmitting member. Thus, when the motor is moved clockwise about its pivot pin 27 and the track 36 is in engagement with the power-transmitting member 24, the said member will move the track element in a counterclockwise direction about its pivot point as it approaches the extremity of said track element. As seen in Figs. 1 and 2, the track element extends slightly beyond the vertical plane passing through the pivot pin of the motor.

An extension 41 is provided on the track element, said extension having one end of a spring 40 secured thereto while the other end of the spring is anchored to any suitable member of the vehicle frame. This spring tends to move the track element in a clockwise direction about its pivot pin 37 until said element engages with the power-transmitting member.

Under certain conditions, however, it is desirable to hold the track element out of engagement with said member. Therefore, there is provided a latch lever 42 which is fulcrumed on pin 43 carried by the platform 23, said lever being moved toward the track extension by spring 44. A detent lug 45 is provided on the latch lever, which is adapted to engage with the end of the extension 41 to hold the track element out of engagement with the power-transmitting member while said latch lever is held in such track-extension engagement.

Carried by the motor vehicle, in any suitable manner, there is a manually-controlled

element or pedal 48, held in normal, inoperative position by means of a spring 49. This pedal 48 includes a stem 50 at the end of which there is carried a bridging element 51 adapted, through operation of the pedal 48, to be brought in bridging engagement with contacts 52 and 53 of the starting switch, thus closing the circuit across this switch which will cause the motor to operate and rotate its shaft 22. A slidable plunger 54 is carried in the stem 50, said plunger extending beyond the edge of said stem and held in this position by means of a blade spring 55 carried on the side of the stem. This plunger 54 is so arranged on the stem 50 that when the pedal 48 is in normal, inoperative position said plunger 54 will be on the motor side of the latch lever 42. The stem is so positioned relative to the platform 23 that upon operation of the pedal, this plunger can engage with said latch lever to operate same out of engagement with track extension 41. A stop 56, however, is provided which limits the movement of said latch lever by the plunger 54, so that when said latch lever engages this stop pin, further movement of said lever is prevented. Continued operation of the pedal 48 will cause the plunger to move transversely through the stem 50 against the effect of the spring 55, thus permitting continued movement of the pedal 49 to cause the plunger to be moved on the side of the latch lever 42 opposite the motor, thereby releasing the latch lever 42 and thus permitting the spring 44 to return said lever into engagement with the track extension 41. Continued movement of the pedal will cause bridging of the contacts 52 and 53.

The operation of the device is as follows:

When the operator desires to start the motor, the pedal 48 is depressed. As has been explained, the plunger 54 will engage with the latch lever 42, moving it counterclockwise around its fulcrum pin 43 against the effect of the spring 44, thereby releasing the extension 41 of the track element 36 and thus permitting the spring 40 to move the said track element 36 clockwise about its pivot pin 37, so that the edge 38 will engage with the power-transmitting element 24. This power-transmitting element will not start to rotate until the contacts 52 and 53 are closed, thus, the motor will remain in its inoperative position, or the position shown in Fig. 1, until the pedal 48 has been operated so that the plunger 54 will move past the latch lever 42, due to said latch lever engaging the stop 56.

As soon as the pedal 48 has been moved sufficiently so as to cause bridging of the contacts 52 and 53, the motor will start to rotate, and due to torque reaction, the power-transmitting element 24 will start to crawl along the edge portion 39 of the track ele-

ment 36 toward the end of said track. As the power-transmitting element approaches the end of the track, it will gain momentum, thus causing the motor to be thrown over the vertical center of its pivot where the weight of the motor is sufficient to carry it the remaining distance, so that the power-transmitting element will engage with the engine flywheel, as illustrated in the drawing.

10 While the power-transmitting element is moving along the track edge portion 39, the track 36 will be moved in a counterclockwise direction about its pivot pin 37, due to the fact that this portion 39 is not radial with 15 the pivotal point of the motor. The counterclockwise movement of the track will again place the extension 41 of the track element in latched relation with the detent lug 45 on the latch lever, this latch lever 20 having been permitted to return to its normal position after the plunger has passed the latch lever by the operation of the pedal 48.

The relative position of the power-transmitting element to the center of the flywheel and its radial center will cause a wedging effect when the rotating power-transmitting element strikes the flywheel, thereby causing said rotating power-transmitting element to 30 in turn rotate the flywheel for cranking purposes. As soon as the engine becomes self-operating, it will rotate at a greater speed than the power-transmitting element and, therefore, throw the motor out of engagement therewith. Being thrown out of engine 35 engagement, the motor will move radially in a counterclockwise direction until the link 25 again engages with the bumper spring 28 at which time the motor will come to rest—it being held in this position by 40 means of the gripping element 30.

If, the operator maintains the pedal 48 in operative position, in which the contacts 52 and 53 are bridged by the element 51, the motor will still continue to rotate. Radial movement of the motor, nevertheless, 45 is prevented because the track element 36 is being held out of engagement with the power-transmitting element 24 and will so be held until the operator releases the pedal 50.

48 Returning the pedal 48 to its normal position will cause the plunger 54 to again engage with the latch lever 42. This latch lever, however, being engaged with the extension 41 of the track element 36, will not move with the plunger 54 so that said plunger will again be moved transversely relative to the stem 50, thereby permitting said plunger to pass the latch lever 42 and 55 again assume its normal position in respect to said lever.

The power-transmitting element 24 has been shown in the form of a friction wheel having a wedge-shaped edge. In order to 60 insure a good gripping effect between the

friction wheel 24 and the flywheel, a V-shaped groove 60 is provided in the flywheel into which said friction wheel is adapted to be shifted, so that the wedging effect of the motor will cause an increased gripping effect of the friction wheel in this V-shaped groove, thereby to overcome the inertia of the engine. 70

While the form of embodiment of the invention as herein disclosed, constitutes a 75 preferred form, it is to be understood that other forms might be adopted, all coming within the scope of the claims which follow.

What is claimed is as follows:

1. A starting device for an internal-combustion engine including a flywheel comprising, in combination, a pivotally-mounted motor having a power-transmitting member; a track adapted to engage with the said member, but normally locked out of engagement therewith; and a manually-operable means for unlocking the track so as to permit it to engage the power-transmitting member and for causing the motor to rotate, 80 whereby the motor will be moved radially about its pivot toward the engine, causing the power-transmitting member to engage the flywheel for cranking purposes. 85

2. A starting device for an internal-combustion engine including a flywheel comprising, in combination, a pivotally-mounted motor having a power-transmitting member; a pivotally-mounted track adapted to be moved into engagement with said member; a latch for holding said track out of engagement with said member; and a manually-operable means for operating the latch to release the track, whereby it will move into engagement with the power-transmitting member, said manual means being adapted 95 also to cause the motor to rotate, whereby the motor will be moved radially about its pivot toward the engine, causing the power-transmitting member to engage the flywheel for cranking purposes. 100

3. A starting device for an internal-combustion engine including a flywheel comprising, in combination, a pivotally-mounted electric motor having a power-transmitting member; a pivotally-mounted track adapted to be moved into engagement with said member; a latch for holding said track out of engagement with said member; a motor switch; a pedal, operable to unlatch the track and close the motor switch whereby the track will engage the power-transmitting member and the motor will rotate, thereby causing the motor to move radially about its pivot for causing the said member to engage with the engine flywheel for cranking purposes. 115 120

4. A starting device for an internal-combustion engine including a flywheel comprising, in combination, a motor pivotally mounted on a standard adjacent the fly- 130

wheel; a power-transmitting member on said motor adapted to engage with the engine flywheel; means carried on said standard for yieldingly holding the motor in flywheel-disengaging position; a pivotally-mounted track adapted to be moved into engagement with the power-transmitting member; a latch adapted to engage said track for holding the same normally out of engagement with the power-transmitting member; and means for operating the latch to release the track so that it will engage the said member, and for causing the motor to rotate, whereby the motor will move radially about its pivot, away from its holding means and into flywheel-engaging position for cranking purposes.

5. A starting device for an internal-combustion engine including a flywheel comprising, in combination, a pivotally-mounted motor having a power-transmitting member; a pivoted track adapted to engage with said member, but normally latched out of engagement therewith; manually-operable 20 means for unlatching the track so as to permit it to engage with the power-transmitting member, operation of said manual means also causing the motor to rotate, whereby the power-transmitting member 25 will crawl along the track, causing radial movement of the motor about its pivot and thereby bring the said member into cranking engagement with the flywheel; the aforementioned track being so constructed and arranged as to be engaged by the power-transmitting member during the radial movement of the motor toward the flywheel, whereby the track is moved into engagement with its latch to hold said track out of 30 engagement with the power-transmitting member while the manual means is maintained in motor-rotating position.

6. A starting device for an internal-combustion engine including a flywheel comprising, in combination, a pivoted motor having a power-transmitting member; a movable track normally latched in inoperative position but releasable to engage said member; manual means for releasing said track and for causing the motor to rotate whereby the power-transmitting member will be moved radially into flywheel engagement; the aforementioned track being constructed and arranged for causing the power-transmitting member to move said track into normal latched position, during the radial move-

ment of said member, whereby, when the said member and the flywheel are disengaged and the motor returned to normal position, said track will be held out of engagement with said power-transmitting member while the manual means is maintained in operated position.

7. A starting device for an internal-combustion engine including a flywheel comprising, in combination, a pivoted motor having a power-transmitting member; a movable track normally latched in inoperative position but releasable to engage said member; a spring for moving and yieldably holding said hinged means in engagement with the power-transmitting member; manual means for releasing said track and for causing the motor to rotate, whereby due to the engagement of the power-transmitting member and the hinged means, the power-transmitting member will be moved radially into flywheel engagement; the aforementioned track having a camming face for causing the power-transmitting member to move said track into normal latched position, during the radial movement of said member, whereby, when the said member and the flywheel are disengaged and the motor returned to normal position, said track will be held out of engagement with said power-transmitting member while the manual means is maintained in motor-rotating position.

8. A starting device for an internal-combustion engine having a rotatable part connected therewith; a motor having a rotatable power-transmitting member movable transversely into engagement with said engine part; a movable track engageable with said member; means for normally latching the track out of engagement with said member; manually-controlled means movable into operating position for releasing the latch to permit the track to engage said member and for causing the motor to operate, whereby the member will move transversely toward the engine part by cooperation with said track; the aforementioned track being so constructed and arranged as to be responsive to the transverse movement of the member for restoring the track to latched position.

In testimony whereof I hereto affix my signature.

WALTER W. RIEDEL.
